(57) **CLAIM**

(**) Term: **14 Years**

The ornamental design for an image reproduction icon for a sound reproduction machine, as shown and described.

(21) Appl. No.: **29/212,253**

DESCRIPTION

(22) Filed: **Aug. 27, 2004**

FIG. 1 is a front elevational view of an image reproduction icon for a sound reproduction machine, showing our new design;

(51) **LOC (8) Cl. 14-04**

FIG. 2 is a front elevational view of a second embodiment thereof;

(52) **U.S. Cl. D14/489**

FIG. 3 is a front elevational view of a third embodiment thereof;

(58) **Field of Classification Search** D14/485-95;

FIG. 4 is a front elevational view of a fourth embodiment thereof; and,

D18/24-33; D19/6; D20/11; D21/324-33;
715/700-866

FIG. 5 is a front elevational view of a portion of the first embodiment shown in FIG. 1, on an enlarged scale.

See application file for complete search history.

The broken line drawing of a sound reproducing machine and the camera and headphone icons are for illustrative purpose only and forms no part of the claimed design.
